UNITED STATES PATENT OFFICE.

GIANNI CAPRONI, OF MILAN, ITALY.

KNOCKDOWN AEROPLANE.

1,357,542.

Specification of Letters Patent.

Patented Nov. 2, 1920.

Application filed June 8, 1918. Serial No. 238,969.

To all whom it may concern:

Be it known that I, GIANNI CAPRONI, a subject of the King of Italy, and residing at Via S. Gregorio 28, Milan, Italy, have 5 invented certain new and useful Improvements in Knockdown Aeroplanes, of which the following is a specification.

This invention has for its object to provide an improved method of joining together the elements of aeroplanes in general, but more particularly of biplanes having two fuselages, especially for the purpose of increasing the rapidity of assembling and disassembling the various parts, and 5 where required, reducing to a minimum the bulk of the entire machine and consequently the space taken up by the machines in their sheds and during transport.

One part of this invention relates to the mounting and dismounting of the fuselages of the central cell; a second part of the invention relates to the mounting and dismounting of the central cell; a third part relates to the construction of the attachment of the landing carriage to the central cell; and a fourth part relates to a peculiar arrangement of the radiators.

In the accompanying drawings a practical form of this invention is illustrated by way of example in its application to a biplane having two fuselages.

In these drawings:

Figure 1 is a front view of the complete machine.

Fig. 2 is a view similar to Fig. 1 but drawn to a larger scale showing some of the parts detached from the others.

Figs. 3 and 4 are respectively a side view and a front view illustrating the forward portion of the car.

Figs. 5 and 6 are respectively a side view and a rear end view of the rear portion of a fuselage.

In the various figures the same numerals are employed to designate the same parts.

—1— is the central cell of the apparatus; —2— and —2'— are the side cells. —3— and —3'— are the longitudinals of the wings. —4— are the uprights. —5— is the car provided with a radiator —8—. —6— and —6'— are the fuselages. —7— is the landing carriage. —9— are the engines. —10— are the respective radiators.

According to this invention the car —5— and the fuselages —6— and —6'— bear exclusively upon the lower plane of the

central cell —1— in such a manner that the lateral cells —2— and —2'— can be detached and dismounted from the central cell independently of the fuselages. 60

In mounting the parts, the attachment of the lateral cells to the central cell is effected (see Fig. 2 which shows the cell —2— detached by way of explanation) by inserting the tie-rods —11— and —11'— into the respective connecting sleeves or sockets —12— and —12'—, and fastening —11— to —12—, and —11'— to —12'— by means of bolts extending right through. 65

The fuselages —6— and —6'— (whereof —6'— is shown detached by way of explanation) are fixed to the central cell by means of bolts —13— to the uprights —4—, and by means of stirrups —14— to the lower longitudinals —3'—. 70

For the purpose of assuring the desired stability of the carriages —7— in the case where the lateral cells are dismounted, and consequently the respective outer cables —15— are disconnected, each upright —16— 80 is provided with a strut —17— for attachment to the central section of the forward lower longitudinal —3'— by means of the stirrups —14—. 75

This improved method of connection 85 serves also to increase the strength and rigidity of the attachment of the fuselages.

For the purpose of facilitating still more the dismounting of the machine and at the same time diminishing the passive resistances, the radiators are shifted in the following improved manner: the radiators —10— are placed in front of and below their respective engines and are united to their respective fuselages. The radiator —8— 90 is placed on the front of the car in such a manner as to be able to serve also to heat the said car internally. For this purpose a temperature regulator is provided in connection with the radiator. 95

Having now particularly described and ascertained the nature of my said invention and in what manner the same is to be performed, I declare that what I claim is:

1. A biplane composed of sectional longitudinals and uprights between the longitudinals forming a central cell and side cells the longitudinal sections of which are detachably connected to the longitudinal sections of the central cell, a landing carriage having uprights rigidly connected with the bottom of the central cell, a main 105 110

fuselage mounted in the central cell, secondary fuselages detachably connected to the lower longitudinal section and the uprights forming the sides of the central cell, 5 and struts detachably arranged between the uprights of the landing carriage and the central cell.

2. A biplane as claimed in claim 1, wherein stirrups are mounted on the lower portion 10 of the central cell and serving as a dual means for fastening the sides of the secondary fuselages and the upper ends of the bracing struts for the landing carriage.

3. A biplane as claimed in claim 1 where- 15 in sockets are formed at the ends of the longitudinal sections forming the central cell, tie rods on the inner ends of the longitudinal sections of the side cells and receivable in the sockets and means for detachably retaining the rods in the sockets.

4. In an improved construction of aero-

planes more particularly of biplanes as claimed in claim 1, the provision of bolt connections between the uprights of said central cell portion and the uprights of said 2 fuselages; stirrup connections between the longitudinals of said central cell portion and the longitudinals of said fuselages.

5. In an improved construction of aeroplanes more particularly of biplanes as 3 claimed in claim 2 socket and plug connections between the longitudinals of the central cell portion and the longitudinals of the lateral portions, bolts to fasten said socket and plug connections, removable strut 3 connections between the carriage uprights and a longitudinal of the lower central cell portion.

In testimony whereof I have signed my name to this specification.

GIANNI CAPRONI.
